UNITED STATES PATENT OFFICE

109,850

DESIGN FOR A CIGARETTE CASE

Anthony Melone, Cranston, R. I., assignor to Paragon Jewelry Company, Providence, R. I., a corporation of Rhode Island

Application November 29, 1937, Serial No. 73,237

Term of patent 3½ years

To all whom it may concern:

Be it known that I, Anthony Melone, a citizen of the United States, residing in the city of Cranston, county of Providence, and State of Rhode Island, have invented a new, original, and ornamental Design for a Cigarette Case, of which the following is a specification, reference being had to the accompanying drawing, forming a part thereof.

Fig. 1 is a perspective view of the cigarette case in closed position, showing my new design;

Fig. 2 is a perspective view of the cigarette case opened; and

Fig. 3 is a sectional view of the cigarette case on line 3—3 of Fig. 1.

The design constituting the subject matter of the present invention is characterized by the integral appearance of the cigarette case which is ornamented on its front face by a serpentine line extending continuously from one end to the other. The ornamental appearance of the cigarette case is further characterized by the angularly related and interleaving fingers on the two halves of the case when the latter is open exhibiting alternate series of plain flat faces and concave recesses on each of the halves.

I claim:—

The ornamental design for a cigarette case, substantially as shown and described.

ANTHONY MELONE.
